JAMES W. BAKER Inventor

Richard L. Owen Attorney

UNITED STATES PATENT OFFICE.

JAMES W. BAKER, OF SANTA CRUZ, CALIFORNIA.

GATE.

Application filed April 12, 1923. Serial No. 631,707.

To all whom it may concern:

Be it known that I, JAMES W. BAKER, a citizen of the United States, residing at Santa Cruz, in the county of Santa Cruz and State of California, have invented certain new and useful Improvements in a Gate, of which the following is a specification.

The present invention relates to gates and more particularly to improved operating means therefor.

The principal object of this invention is to provide a road gate having means for moving the gate across the road by a gravity actuating mechanism.

Another object of this invention is to provide a road gate having means for opening and closing the same that can be operated by a vehicle as the same approaches the gate thus obviating the numerous inconveniences occurred when it is necessary to leave the vehicle to open a gate and afterwards close the same.

Another important object of the invention is to provide a gate of this nature which is simple and efficient in construction, reliable in operation, durable, inexpensive to construct, and well adapted to the purpose for which it is designed.

With the above and numerous other objects in view as will appear as the description progresses, the invention resides in certain novel features of construction, and in the combination and arrangement of parts as will be hereinafter more fully described and claimed.

For the purpose of illustrating my invention, I have shown in the accompanying drawing that form thereof which is at present preferred by me, since the same will give in practice satisfactory and reliable results, although it is to be understood that the various instrumentalities of which my invention consists can be variously arranged and organized and that my invention is not limited to the precise arrangement and organization of these instrumentalities as herein shown and described.

In the drawing—

Figure 1 is an elevation of the gate in a closed position,

Figure 2 is a similar view showing the gate in an open position,

Figure 3 is a top plan thereof,

Figure 4 is a side elevation of the operating mechanism for the gate,

Figure 5 is a detail view showing the trip and crank operated thereby,

Figure 6 is a detail view showing particularly the operating lever for the tracks of the gate, and

Figure 7 is a detail section taken substantially on the line 7—7 of Figure 6.

Referring to the drawing in detail it will be seen that the gate frame A consists of the beam 1 which is supported by the end standards 2 and 3 and the intermediate standard 4. These standards 2, 3 and 4 are preferably embedded in the ground but, of course, may be supported in any other desired manner. The roadway is disposed between the standards 3 and 4 and in the usual use of the gate the distance between the standards 2 and 4 would be within an enclosure. The gate B may be of any general preferred construction and the embodiment herewith disclosed is merely given by way of example to illustrate the operation thereof and includes the cross rods 6 braced as at 7 and connected at their ends to the standards 8. These standards 8 project upwardly from the gate and have journaled in their upper ends suitable rollers 9 which are preferably of the grooved type such as is illustrated to advantage in Figure 7. The track which is engaged by these rollers 9 is indicated generally at C and includes a track lever 10 which is fulcrumed at 11 to the beam 1 between the standards 3 and 4 and the track lever 12 which is fulcrumed at 13 between the standards 2 and 4. The track lever 10 is constructed at the end adjacent standard 4 with a slot 14. The track lever 12 is constructed with a slot 15 adjacent the standard 4 while the other end thereof is curved to provide an upwardly extending hooked extension 16. An operating lever 17 for the track levers 10 and 12 is fulcrumed intermediate its ends to the beam 1 preferably immediately above the standard 4. This lever 17 includes a pair of curved or arcuate arms 18 having projecting pins at their terminals as at 19 for penetrating the slots 14 and 15. From the description as it has thus far progressed it will be readily seen that if the track lever 10 is shifted from the position shown in Figure 1 to the position shown in Figure 2 that the lever 17 will actuate the track lever 12 to the position shown in Figure 2 from that shown in Figure 1 whereby the two track levers will be inclined in an opposite direc-

tion.

Figure 1 is an elevation of the gate in a closed position,

Figure 2 is a similar view showing the gate in an open position,

Figure 3 is a top plan thereof,

Figure 4 is a side elevation of the operating mechanism for the gate,

tion from that shown in Figure 1 so that gravity will cause the gate to move to an open position. Of course this operation is readily reversed by suitable operation of the lever 10. Particular attention is called to the fact that the hooked extension 16 forms a seat for one of the rollers 9 when the gate is in an open position as does one of the arms 18 of the lever 17 and these 10 act as stops. It is also to be noted that the various elements are proportioned and disposed so that when the gate is in a stationary position that is either closed or open it will be properly disposed that is not tilted 15 but positioned so that the standards 8 are in a vertical position and the rods 6 in a horizontal position.

An understanding of the operating mechanism for the gate about to be described 20 can best be had by particular reference to Figures 3 and 4. A post 25 is disposed alongside of the standard 3 a slight distance therefrom and similar posts 26 and 27 are disposed in alignment with each other and 25 with the post 25 so as to be aligned at right angles to the alignment of the standards 2, 3 and 4, that is so as to be disposed alongside of the roadway. A pair of levers 28 are fulcrumed to the posts 26 and 27 intermediate their ends, one to each post and the 30 ends of these levers 28 are slotted as at 29. A lever 30 is fulcrumed intermediate its ends to the post 25 and is provided at one end with a pin 31 engaging the slots of 35 the levers 28 at their adjacent ends whereby this lever 30 may be actuated by either of the levers 28.

A link rod 32 is fulcrumed to the other end of the lever 30 and is fulcrumed to the outer 40 end of the track lever 10. From the description as it has thus far progressed it will be seen that the gate may be operated by the actuation of either lever 28 through the mechanism described. Each lever 28 45 has its own operating mechanism which are similarly constructed and include a rod or shaft 34 embedded in the ground as is illustrated to advantage in figure 1 and journaled on blocks 35 or in any other suitable manner. A trip lever 35 is formed on the shaft 34 adjacent one end and a similar trip lever 36 50 is fixed to the other end thereof. These levers 35 and 36 are so disposed that when one is up the other is down. The trip lever 55 35 actuates the mechanism for opening the gate while the trip mechanism 36 actuates the mechanism for closing the gate. At one end the shaft 34 terminates in a crank 37 which engages a slot 29 in the adjacent lever 28.

In considering the device especially as it is illustrated in Figure 3 it will be seen that as a vehicle approaches from the left the wheels thereof will engage the trip arm 35 60 which is in a raised position which will

actuate the mechanism to open the gate. When the vehicle has passed through the gateway the vehicle wheels will ride over the trip lever 36 which has been raised 70 causing the gate to close. To consider this operation in detail it will be seen that when the trip lever 35 is depressed it will turn the shaft 34 journaled on blocks 35' causing the rotation of the crank 37 which in turn will fulcrum the adjacent lever 38 causing the rotation of lever 30 which will pull downwardly upon the link rod 32. This link rod 32 will then fulcrum the track lever 10 which in turn will fulcrum the lever 17 causing the track lever 12 to be fulcrumed 80 and thus gravity will cause the gate to move to an open position. This operation is practically reversed when the trip lever 36 is depressed on the other side of the gate since 85 it will be noted that this trip lever 36 will be raised when the opposite trip lever 35 is depressed because the rotation of the lever 30 will cause the other lever 28 to be fulcrumed which will actuate the other crank 37 and shaft 34 to depress the other trip lever 35 and elevate the opposite trip lever 36.

From the foregoing description, taking in connection with the accompanying drawing, the construction and operation of the gate will be readily understood without a more extended explanation. As numerous changes in form, proportion and in the minor details of construction may be resorted to without departing from the spirit of the invention, 100 I do not wish to be limited to the construction herein shown and described other than as claimed.

Having thus described my invention what I claim as new is:—

1. In combination, a frame, a lever pivoted to the frame, a pair of track levers pivoted to the frame one on each side of the first mentioned lever, a pin and slot connection between the track levers and the first mentioned lever so that the track levers may be inclined in parallelism, and a gate slidably engaged with the levers so that by shifting the inclination of the levers the gate may be moved to an open or closed position, said first mentioned lever being provided with arcuate arms one on each side of its fulcrum point so as to form rests for the gate.

2. In combination, a frame, a pair of track levers fulcrumed on the frame one on each side of its center, another lever fulcrumed to the frame between the first mentioned levers and including a pair of arcuate arms one disposed on each side of its fulcrum point, a pin and slot connection between the pair of first mentioned levers and the last mentioned lever, one of said first mentioned levers terminating in a hooked extension, a gate including a pair of rollers one engaged with each of the first mentioned levers

whereby the first mentioned levers may be inclined so that the gate will shift to an open or closed position in the manner and for the purpose specified.

- 5 3. In combination, a frame, a lever fulcrumed to an intermediate portion of the frame, a pair of track levers fulcrumed to the frame one each side of the first mentioned lever, a pin and slot connection between the first lever and the adjacent ends of the pair of track levers, a gate slidable on the levers so that when they are inclined the gate will move to an open or closed position, a pair of operating levers fulcrumed 10 so as to extend alongside of a roadway adjacent the gate, means for fulcruming the operating levers, an auxiliary lever fulcrumed alongside of the frame, a pin and

slot connection between the operating levers and the auxiliary lever, a link connection 20 between the auxiliary lever and one of the track levers, and trip mechanisms associated with the operating levers, each trip mechanism including a shaft having a crank at one end engageable with one of the operating rods for fulcruming the same, a pair of trip arms extending from the shaft at angles to each other so that when one is down the other will be up all in the manner and for the purpose specified. 25

In testimony whereof I affix my signature in presence of two witnesses.

JAMES W. BAKER.
